UNITED STATES PATENT OFFICE.

LUDVIG MATTSON, OF EVANSTON, ILLINOIS.

SAFETY SERVICE-HOLDER.

1,267,098.

Specification of Letters Patent. Patented May 21, 1918.

Application filed December 12, 1917. Serial No. 206,742.

To all whom it may concern:

Be it known that I, LUDVIG MATTSON, a subject of the King of Sweden, residing at Evanston, in the county of Cook and State 5 of Illinois, have invented certain new and useful Improvements in Safety Service-Holders, of which the following is a specification.

This invention relates to improvements in 10 a device to be used for holding articles of dining service, such as plates, cups and saucers, glasses, bottles, knives and forks, and containers for condiments and the like, against displacement, or, so that they will 15 not tilt or tip over, and while it is more especially intended for use on board sea-going ships or vessels, and to be fixed to the dining tables thereof, yet it is applicable for use in connection with serving trays, such as 20 are used by waiters on ships, in restaurants, hotels, and other places where foods and refreshments are served, and it consists in certain peculiarities of the construction, novel arrangement and operation of the various 25 parts thereof as will be hereinafter more fully set forth and specifically claimed.

The principal object of the invention is 30 to provide a service holder of the above described general character which shall be attractive in appearance and efficient in holding the receptacles for food and the like, or those containing food or liquids, against displacement or tipping over by reason of the rolling or tossing of the vessel, or by reason 35 of the careless handling of the tray to which it may be attached.

Another object is to provide individual service holders which can be readily attached to the table at proper places so that 40 one will be directly in front of each guest when seated at the table, or can be easily detached and removed with the entire service for each guest. Other objects and advantages of the invention will be disclosed in 45 the subjoined description and explanation.

In the accompanying drawings which serve to illustrate an embodiment of the invention,

Figure 1 is a plan view of the device 50 showing it mounted on a portion of a table or tray.

Fig. 2 is a view in side elevation looking from the edge of the table or tray to which the device is secured.

Fig. 3 is a sectional view taken on line

3—3 of Fig. 1 looking in the direction indicated by the arrows.

Fig. 4 is a detached perspective view of one of the retaining members for a bottle or glass. 60

Fig. 5 is an enlarged sectional view taken on line 5—5 of Fig. 1 looking in the direction indicated by the arrows.

Fig. 6 is a detached perspective view of a retaining member for stem glasses, and 65

Fig. 7 is a view of a portion of a coffee or tea pot with a retaining member therefor attached thereto so that said part or vessel can be supported by the holder.

Like numerals of reference refer to corresponding parts throughout the different views of the drawings. 70

Referring now to Figs. 1, 2 and 3 of the drawings, the reference numeral 10 designates a portion of a table top or a part of 75 a tray on which the service holder is mounted. For the sake of brevity and clearness of description, the part 10 will be referred to as the support for the holder, but I wish it distinctly understood that it may be either 80

a part of the top of a table or a part of a tray. The holder consists of a ring 11 which by preference has its lower surface flattened as shown in Fig. 3, so as to lie closely on the upper surface of the support 85

10 or table cloth when said support is used as a table. The upper surface of the ring 11 is rounded cross sectionally as shown and said ring is of sufficient size to permit a plate or soup dish to be placed therein so that its 90

base will rest on the support 10 while the ring 11 will circumscribe said base. At its outer portion or that portion thereof adjacent to the edge of the support to which the holder is secured, the ring 11 is provided 95

with a pair of upwardly extended projections 12 which have their upper ends turned inwardly as at 13 as is clearly shown in Figs. 2 and 3 of the drawings. Extended from the ring 11 at points diametrically opposite each other are portions 14 and 15 which have their lower surfaces flattened to lie closely on the support. The portion 14 is extended downwardly as at 15^a and then inwardly or forwardly as at 16 to lie under 100 the support 10. This forwardly projecting portion 16 is provided with a screw threaded opening 17 in which is located a set screw 18 used for fastening the holder to the support as will be readily understood by refer- 105

110

ence to Fig. 3 of the drawings. At its front end the portion 15 is connected to a transversely extended box 19 which is for the reception and retention of knives, forks, 5 spoons and the like, and which is provided on its wall adjacent to the ring 11 with a rearwardly extended lug 20 to overlie the plate or dish held by the ring 11, which lug in conjunction with the upright projections 10 12 on said ring, will prevent the plate or dish being accidentally slid or displaced. The front wall of the box 19 is provided with a number of vertical sockets 21 to receive the stems 22 of the retaining rings 15 or members 23 which may be of suitable sizes to receive and hold bottles or glasses of different sizes, which articles are placed within the retaining members 23 so that their lower ends may rest on the support. 20 As shown in Fig. 4, the stem 21 of each of the retaining members 23 has a flat wall 24 to rest against the inner surface of the front wall of the box 19, while the rear surface of said stem is rounded to fit the curved 25 portion of the socket 21 in which it may be located. By this arrangement, it is apparent that the retaining member 23 will be prevented turning in its socket. In order to adjust the retaining member 23 vertically, 30 each of the sockets 21 is provided with a set screw 24^a to engage the stems 21 so as to hold them at the proper height to accommodate bottles or glasses of different lengths. Each of the end walls of the box 35 19 is also provided with a vertical socket 21, each having a set screw 24^a seated therein. In one of the end sockets 21 is fitted the stem 25 of a retaining member for stem glasses 26, see Figs. 1, 2 and 6 of the drawings. The said retaining member consists of a stem 25 having a portion of its wall flattened as at 27 and the other part thereof rounded to fit the curved portion of the socket 21 in which it is located where said 40 45 stem may be adjustably held by means of the set screw 24^a. Extended from the upper portion of the stem 25 laterally and then downwardly is an arm 28 which has its lower end extended laterally and provided 50 with a clamp 29 to receive the stem of the glass as is clearly shown in Fig. 2 of the drawings. In the socket 21 at the opposite end of the box 19 is located the stem 30 of a retaining member for a coffee or tea 55 cup, which member consists of the stem 30, and an outwardly and downwardly extended arm 31 which terminates in a pair of curved arms 32 which lie in a horizontal plane, yet with their free ends spaced apart 60 to permit of the insertion of the handle 33 of the cup 34 therebetween as is clearly shown in Fig. 2 of the drawings, in which view it will be seen that the arms 32 are connected by means of uprights 35 with a ring 36 which 65 is of greater diameter than the broken ring formed by the arms 32 which surround the top of the cup and said ring 36 has supporting legs 37 to rest on the support and around the saucer 38 so as to prevent the latter sliding or becoming displaced with 70 respect to the cup. The stem 30 of the retaining member for the cup may be adjustably secured in place by means of the set screw 24^a seated in the socket 21 for said member. The wall of the box 19 adjacent 75 to the ring 11 is provided near each of its ends with a rearwardly extended band 39 which are adapted to rest at their lower edges on the support 10 and have in their upper edges a series of recesses 40 to receive 80 projections 41 on plates or disks 42 which are of sufficient size to fit snugly within said bands and are provided with openings 43 to receive condiment holders such as salt and pepper shakers, vinegar bottles, mustard 85 jars and the like (not shown). By means of the projections 41 of the disks or plates 42, it is obvious that the latter may be easily removed from the bands 39 or placed in position therein. 90

In Fig. 7 of the drawings is shown a portion of a coffee or tea pot 44 on the wall of which is secured a bracket 45 which is of proper size and shape to fit in any of the sockets 21 of the box 19 where it may be fastened by means of one of the set screws 24^a in such a way as to allow the bottom of the vessel 44 to rest on the support, yet so as to prevent it tipping over. 95

From the foregoing and by reference to 100 the drawings, it will be understood that the retaining members for glasses, bottles, and cups are interchangeable with one another and can be located as desired with respect to the box 19, and that the disks 42 are also interchangeable, that is, either one can be placed in the desired band 39 or retainer therefor. Of course, small butter plates can be used instead of disks 42 and will be prevented from dislocation by means of the 105 bands 39 in which they may be located. It will be further understood that the ring 11 and box 19 are rigidly connected together and that by means of the extension 16 and set or thumb screw 18, the device can be 110 readily and firmly attached to the support 10 whether it be a table or a waiter's tray. 115

Having thus fully described my invention, what I claim as new and desire to secure by Letters Patent is— 120

1. In a safety service holder, the combination with a ring having a box connected thereto and located at one of their surfaces in substantially the same plane, of means to detachably secure said ring to a support, the 125 said box having a plurality of vertical sockets in its walls, the said ring having a plurality of upwardly and inwardly extended projections, and retaining members, each having a stem adapted to fit in said sockets, 130

2. In a safety service holder, the combination with a ring and a box connected together and located at one of their surfaces in substantially the same plane, of means to 5 detachably secure said ring to a support, the said box having a plurality of vertical sockets in its walls and one or more horizontally disposed bands on one of its walls, the said ring having a plurality of upwardly and in-

wardly extended projections, retaining members for service articles each having a stem adapted to fit in one of said sockets, and disks or plates removably located in said bands.

LUDVIG MATTSON.
